The ornamental design for a dish rack as shown and described.

DESCRIPTION

FIG. 1 is a perspective view of a dish rack showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of an indicated portion of FIG. 1;

FIG. 9 is an enlarged view of an indicated portion of FIG. 2; and,

FIG. 10 is another perspective view showing the dish rack installed at a base with other dish racks.

The broken line portions of the dish rack in FIGS. 1-10 represent unclaimed portions of the claimed design and form no part thereof. The broken lines of the base and other dish racks in FIG. 10 illustrate unclaimed environment and forms no part of the claimed design. The dot-dash broken lines in FIGS. 1-5 and 7-10 represent unclaimed boundary lines and form no part of the claimed design.
